UNITED STATES PATENT OFFICE.

EDWARD WESTON, OF NEWARK, NEW JERSEY.

DESIGN FOR A MAGNET.

SPECIFICATION forming part of Design No. 20,318, dated November 18, 1890.

Application filed October 14, 1890. Serial No. 368,125. Term of patent 14 years.

To all whom it may concern:

Be it known that I, EDWARD WESTON, of Newark, Essex county, New Jersey, have invented and produced a new and original Design for a Magnet, of which the following is a specification, reference being had to the accompanying drawing, which represents a perspective view with a portion of the object broken away in order to exhibit a part otherwise obscured.

My design is intended to be applied more particularly to the magnets of electrical measuring-instruments, and consists in the hollow cylindrical body A, having two flat heads or faces D and D. Protruding from the outer

surface of the head B appears a tubular extension C. Protruding from the inner surface of the head D appears a cylindrical extension E. The cylindrical extension E is concentric with the tubular extension C, and there is an annular space between said parts C and E. The protruding portions C and D are the poles of the magnet.

I claim as my invention.

The design for a magnet, substantially as herein shown and described.

EDWARD WESTON.
